CLAIM

The ornamental design for a sonar device for fishing as shown and described.

DESCRIPTION

The patent or application file contains at least one drawing executed in color. Copies of this patent or patent application publication with color drawing(s) will be provided by the Office upon request and payment of the necessary fee.

1. Sonar device for fishing

1.1 : Front

1.2 : Back

1.3 : Left

1.4 : Right

1.5 : Top

1.6 : Bottom

1.7 : Perspective

(Continued)

1.1 is a front view; **1.2** is a rear view; **1.3** is a left view; **1.4** is a right view; **1.5** is a top view; **1.6** is a bottom view; **1.7** is a perspective view.

1 Claim, 7 Drawing Sheets
(7 of 7 Drawing Sheet(s) Filed in Color)
